UNITED STATES PATENT OFFICE

HARRY F. GERHARDT, OF CHICAGO, ILLINOIS

DESIGN FOR A REFRESHMENT STAND

Application filed May 21, 1932. Serial No. 43,867. Term of patent 14 years.

To all whom it may concern:

Be it known that I, HARRY F. GERHARDT, a citizen of the United States, residing at Chicago, in the county of Cook and State of Illinois, have invented a new, original, and ornamental Design for a Refreshment Stand, of which the following is a specification.

The figure is a front perspective of a refreshment stand, showing my new design.

The exterior outline is generally symmetrical as indicated in the drawing, and the counters and seats shown in the interior are omitted from the rear of the design.

I claim:

The ornamental design for a refreshment stand as shown and described.

In testimony whereof I affix my signature.

HARRY F. GERHARDT.
